PULP DECOY

Arthur H. Risch, Wauwatosa, Wis., assignor to
Pulp Reproduction Company, Milwaukee, Wis.,
a corporation of Wisconsin

Application September 5, 1946, Serial No. 694,939

3 Claims. (Cl. 43—3)

1

The present invention relates generally to improvements in the art of producing molded articles from fibrous pulp or the like, and relates more particularly to improvements in the construction and method of producing aquatic decoys.

A primary object of my present invention is to provide an improved hunter's decoy which is simple and durable in construction and highly efficient in use, and which is especially adapted to be produced primarily of relatively light and inexpensive material such as fibrous pulp.

In hunting and related sports, it has long been customary to use life-like imitation decoys to attract the game to localities selected by the hunter. For many years, such decoys were produced of wood either by hand carving or by machine; but in more recent years, decoys molded or otherwise formed of relatively light and inexpensive materials such as paper pulp have become extremely popular and extensively used by hunters. However, in the manufacture of light weight molded pulp decoys, it is necessary to provide means for causing the pulp shell forming the body to float and to be maintained in upright position on the water. Furthermore, during the suction molding process, an opening must be left in the decoy body for introduction of the pulp stock into the forming mold, and this opening must subsequently be tightly sealed in order to prevent possible leakage of water into the hollow externally-waterproofed body. In the manufacture of molded pulp decoys, it has heretofore been the practice in some instances to introduce the pulp stock into the mold through an opening in the recessed bottom of the body, thereafter covering the opening by means of a buoyant plate or board confined and retained within the recess by suitable means such as a bar pivotally mounted on the board and cooperable with an inner portion of the decoy body in the manner of a latch. In other cases, it has been the practice to introduce the pulp stock through an opening in the top wall of the decoy body and to subsequently plug the opening while providing a separate buoyant plate for the imperforate bottom, the buoyant plate either being fitted into a recess or being secured in a suitable manner directly to the substantially flat bottom. Although various sealing and adhesive substances such as pitch have heretofore been used in efforts to secure the righting boards in place and eliminate leakage, considerable difficulty has been encountered in these prior attempts to produce effective seals because of the failure to eliminate formation of air bubbles in the adhesive or the like during applica-

tion. While these prior molded pulp decoys have been manufactured, sold and used by the thousands with great success, the buoyant righting boards and/or sealing plugs required careful fitting and sealing in order to prevent the possible seepage of water into the hollow pulp bodies during the long periods of exposure to the water while in use and production was somewhat complicated in the various assemblages heretofore proposed in efforts to eliminate or prevent such possible leakage.

It is therefore a more specific object of my present invention to provide an improved hollow molded pulp decoy wherein the hollow body interior is effectively sealed and the disadvantages attendant the prior art structures are obviated.

Another specific object of this invention is to provide an improved hollow molded pulp decoy wherein the pulp stock is introduced into the mold through an opening in the bottom of the decoy body with the bottom opening being closed by a buoyant balancing and righting board and effectively sealed in a simple and novel manner.

Another specific object of my invention is to provide an improved hollow pulp decoy having the bottom opening closed by a buoyant plate and sealed against seepage of liquid in an efficient manner without the use of mechanical expedients such as special latch elements, screws or bolts.

Another specific object of the present invention is to provide an improved aquatic pulp decoy assemblage which may be readily manufactured and assembled at moderate cost, and which is adapted to effectively withstand considerable abuse and hard usage.

A further specific object of this invention is to provide an improved fibrous pulp decoy which is highly attractive and lifelike in appearance, which is composed of a minimum number of available parts, and which will automatically assume upright or natural position when floating.

Still another specific object of the invention is to provide an improved exceedingly strong and durable light-weight decoy which may be readily formed primarily of inexpensive paper pulp in accordance with an improved and simple method with the aid of standard pulp molding equipment at low cost.

These and other specific objects and advantages of the present invention will be apparent from the following detailed description.

A clear conception of the features constituting my present invention, and of the method in which the improved decoys may be commercially produced, may be had by referring to the drawing

accompanying and forming a part of this specification, wherein like reference characters designate the same or similar parts in the various views.

Fig. 1 is a central longitudinal vertical section through a typical swimming duck type of hunter's decoy, embodying an inset wooden base board applied and sealed in accordance with my present invention;

Fig. 2 is a bottom view of the duck decoy of Fig. 1, portions being broken away to reveal internal structure; and

Fig. 3 is a central transverse vertical section through the same decoy.

While the invention has been shown and described herein as being advantageously applied to a typical molded pulp hunter's decoy of the swimming or floating type, it is not my desire or intent to thereby unnecessarily restrict or limit the utility of the improvement, since the invention may obviously be more generally applied to various other types of decoys formed with hollow bodies and of any suitable moldable material such as newsprint pulp, papier-mâché, or plastics.

Referring to the drawing, the typical duck decoy shown therein as embodying the invention comprises in general, a relatively light hollow shell of approximately uniform thickness forming a body 5 of molded fibrous material such as paper pulp, the body 5 having a substantially flat base 6 provided with an elongated downwardly open recess 7 having the bounding wall thereof terminating in an upper inwardly directed flange 8 to provide an opening 9 for feeding pulp stock to the mold and through which access may be obtained for coating the interior of the shell 5 with asphalt, tar, pitch or other adhesive and water-proof material 10; a flat balancing or righting board 11 impregnated and coated with a material such as tar or pitch 12 to snugly confine and adhesively secure the same within the lower recess 7 against the upper flange or wall 8 thereof; a heat sealed cloth or metallic composition foil 13 such as "Plastine" adhesively secured to and covering the bottom of the board 11, the cloth or foil 13 extending beyond the edges of the board to seal the joint between the board 11 and the wall of the recess 7; and a relatively thick layer of asphalt, tar or the like 14 spread over the cloth 13 to substantially fill the recess 7.

The body 5 and the integral side walls and upper wall 8 of the decoy may be simultaneously molded of fibrous pulp in the well-known type of suction molding machine, with the pulp stock being fed through the opening 9 in the wall 8. The righting and balancing board 11 is preferably formed of a durable wood, and should be shaped to reasonably snugly fit within the recess 7 with sufficient space remaining between the bottom surface of the board 11 and the lower surface of the first base 6 to accommodate the cloth 13 and layer of asphalt 14 or the like which preferably extends throughout the entire horizontal area of the board 11 as well as the recess 7.

In actual production of the improved pulp decoys embodying my invention, the hollow bodies 5 may be initially produced with standard suction molding machines in a well known manner with recesses 7 formed in the bases thereof, the pulp being fed to the molds through the openings 9. After such initial step, the interiors of the shells 5 may be impregnated or coated with a water-proof material such as asphalt, tar or pitch. 70

Thereafter, the boards 11 are dipped in a molten adhesive water-proof material such as used for coating the shell interiors and are positioned within the recesses and against the integral stop flanges 8 to close the openings 9. The heat-sealed cloth or foil sheets 13 may then be positioned over the impregnated boards 11, being secured thereagainst by the adhesive; and finally with each body 5 in inverted position, a quantity of molten adhesive material such as hot asphalt, tar or pitch is poured within the recess 7 over the heat-sealed sheet 13 so as to provide a sealing layer 14 of the adhesive which hardens as it dries.

During the process of assembling the decoys, 15 the boards 11 should be positioned and firmly pressed in place within the recesses 7 immediately after dipping and before the molten adhesive coating has had time to set or harden; and the cloth or foil sheets 13 should likewise 20 be applied while the adhesive is still molten and tacky. The heat-sealed sheets 13 thereby seal the boards which invariably contain a considerable amount of moisture, from the final layer or deposit of molten adhesive, and in addition, 25 these sheets serve to absorb a certain amount of heat from the molten adhesive, thereby eliminating formation of bubbles otherwise occurring in the layers 14. As the adhesive cools and hardens, the various parts become thoroughly adhesively 30 attached and all of the joints are effectively sealed against leakage. The various parts coated with the adhesive are likewise water-proofed and reinforced thereby, and the body exterior may finally be suitably water-proofed and painted or 35 otherwise decorated.

From the foregoing detailed description, it will be apparent that the present invention provides an improved decoy assemblage and method of producing the same which is both simple and 40 efficient. Decoys made in accordance with the invention are light and durable in construction and are effectively protected against moisture and possible leakage in addition to being self-righting while afloat. By having the opening 45 for introduction of the pulp stock in the base, the righting and balancing board serves to cover the opening without need for additional plugs; and this board is firmly secured and maintained in place within the recess with all joints being effectively sealed and the parts waterproofed by means of the adhesive. The application of the molten adhesive is simple and formation of air or 50 water bubbles or blisters in the adhesive is effectively eliminated through use of the heat-sealed sheet 13 which seals the molten adhesive during application from the board which invariably contains moisture. This sheet 13 also absorbs some of the heat of the molten adhesive, thereby aiding in more rapidly cooling the molten material; and by virtue of the use of molten adhesive which 55 hardens upon cooling and the use of which is rendered practical and highly successful because of the heat-sealed sheet, a simple and efficient means is provided both for attaching the board 11 in place without resorting to the use of special fasteners as well as for sealing the boards without the need for providing an opening other than in the decoy base for the introduction of pulp stock and the attendant need for separate plugs. Obviously the improved assemblage is simple and 60 decoys produced in accordance with the improved method may be rapidly produced at low cost and in large quantities, and attractive, durable, and light weight decoys which may be manufactured.

with standard suction molding equipment are provided.

It should be understood that it is not desired or intended to limit this invention to the exact details of construction or to the precise mode of production herein shown and described, for various modifications within the scope of the appended claims may occur to persons skilled in the art.

I claim:

1. A molded decoy comprising, a hollow body of molded material having a bottom recess, a righting board confined entirely within said recess, a sealing sheet disposed over the external surface of said board also within said recess, said sheet extending beyond the edges of said board and overlapping the adjacent portions of said body, and a layer of adhesive sealing material covering said sealing sheet within said recess.

2. A molded decoy comprising, a hollow body of molded material having a bottom recess, a righting board confined entirely within said recess, a sealing sheet disposed over the external surface of said board also within said recess, and a layer of adhesive sealing material covering said sealing sheet within said recess.

5 3. A molded decoy comprising, a hollow body of molded material having a bottom recess, the wall of said body adjoining said recess forming an opening to the body interior surrounded by a continuous flange formed integral with said wall, a righting board confined entirely within said recess and coacting with said flange to completely close the opening, a sealing sheet disposed over the external surface of said board

10 also within said recess, and a layer of adhesive sealing material covering said sealing sheet within said recess.
